* UNITED STATES PATENT OFFICE.

EARL B. LEAR, OF PHILLIPSBURG, NEW JERSEY, ASSIGNOR TO INGERSOLL-RAND COMPANY, OF JERSEY CITY, NEW JERSEY, A CORPORATION OF NEW JERSEY.

DOUBLE-DRUM HOIST.

Application filed March 18, 1924. Serial No. 699,968.

To all whom it may concern:

Be it known that I, EARL B. LEAR, a citizen of the United States, and a resident of Phillipsburg, county of Warren, and State of New Jersey, have invented a certain Double-Drum Hoist, of which the following is a specification accompanied by drawings.

This invention relates to hoists but more particularly to an improved clutch mechanism for a power driven hoist of the double drum type, in which either drum may be driven from a common driving shaft.

In some respects, this invention is an improvement on the double drum hoist described and claimed in United States Patent No. 1,421,183, granted to Jesse Ditson on June 27, 1922. By means of this invention, the clutch mechanism is moved to drive one or the other of the drums, in accordance with the direction of rotation of the driving shaft.

The objects of this invention are to produce an improved clutch mechanism for double drum hoists, so as to insure the engagement of the clutch mechanism with one or the other of the drums, in accordance with the direction of rotation of the driving shaft.

Further objects of the invention will hereinafter appear and to these ends the invention consists of the hoist described and claimed in this specification, and shown in one of its preferred forms in the accompanying drawings, in which

Figure 1 is a longitudinal sectional elevation of the double drum hoist.

Figure 2 is a transverse section taken on the line 2-2 of Figure 1 looking in the direction of the arrows, and,

Figure 3 is a perspective view of the pawl and guide member.

Referring to the drawings, the base plate A on which the hoist is mounted is provided with a clamping member preferably in the form of a saddle member B having clamping bolts C for securing the hoist to a column, cross bar, or other support. Any suitable motor may be provided for the hoist, and in this instance, a fluid pressure motor is indicated comprising the cylinder D mounted on the frame E suitably secured to the base plate A. A cylinder head G is

secured to the cylinder by the cap bolts H and fluid pressure, as for instance compressed air, is supplied to the motor through the inlet J controlled by a suitable valve K in the valve chest L, and manipulated by the valve lever O. In this instance, the motor is assumed to be a reversible motor, the reversal of which is controlled by a valve lever O. An oiling device P of any suitable type may be applied to the motor.

A center bearing Q, shown in this instance in the form of a shell, having a tubular body and a flanged portion R, is connected to the motor cylinder D and the cylinder head G by means of cap bolts H. The opposite end of the center bearing is supported in the gear box S, which is secured to the base plate A in any suitable manner. A center bearing retaining screw U suitably secures the center bearing to the inner wall V of the gear box S. An oiling device W may be provided upon the gear box and the gear box cover X is secured to the gear box S by means of bolts Y. The construction of the motor and frame so far described forms a simple and compact frame for the hoist, easily assembled and dis-assembled and permitting ready accessibility to the operative parts of the hoist. A main driving shaft a passing centrally through the center bearing Q is supported in the ball bearings b and c and provided with a crank disc d having the crank pin e connected to the piston f of the motor, by means of ball bearings g, so that the driving shaft a operates throughout in ball bearings.

A driving pinion h is keyed to the driving shaft a and a retaining washer j is held against the driving pinion by means of a pin k. The driving pinion h meshes with an intermediate gear o keyed to the counter shaft p operating in the ball bearings q and r mounted in the gear box S. An intermediate pinion s on the counter shaft p meshes with the internal gear t of the main driver u, adapted to rotate on the center bearing Q from which power is taken for driving either one of the two drums.

A haulage drum v to which one length of the rope w is adapted to be connected, rotates on the center bearing Q and the concentric tail rope drum x to which the tail rope y is connected, preferably rotates upon

the haulage drum v . Such construction of concentric drums materially reduces the overall length of the hoist, and produces a more compact and better balanced hoist than heretofore.

Means are provided for automatically connecting the main driver u to one or the other of the drums v and x in accordance with the direction of rotation of the driving shaft a , and for this purpose, the haulage drum v is provided with a driver z preferably in the form of a ring, having clutch members in the form of teeth 2 merging into cam surfaces 3. The driver z is suitably secured to the haulage drum v by means of the bolts 4 and for convenience of description may be termed the inner driver.

The tail rope drum x is likewise provided with a driver 5 preferably in the form of a ring, having clutch members in the form of teeth 6 facing in the opposite direction from the teeth 2 on the driver z and merging into the cam surfaces 7. The driver 5 is secured to the tail rope drum x by means of bolts 8 and for convenience of description may be termed the outer driver. The spaced teeth 2 and 6 of each series on the opposed drivers, preferably extend radially or in the plane of the respective driver on which they are formed.

The terms inner and outer, as applied to the opposed drivers z and 5 carried by the drums respectively, are not to be understood as necessarily limiting the ratchet ring concentric with the axis of rotation of the machine, but are intended to be used as suitable designations for two opposed ratchet faces for the drums, having reference to some fixed point of the machine, which obviously need not be the driving shaft.

The main driver u is provided with a movable clutch member 9, preferably in the form of a pawl slidable between the lugs 10 projecting inwardly from the main driver u to a position between the inner driver z and the outer driver 5, so that the pawl 9 may engage the inner or outer driver, in accordance with the direction of rotation of the driving shaft a .

The pawl 9 as shown, is separate from but carried wholly by the main driver u and is mounted upon the body portion of the main driver at a point rearward or at a substantial distance in a radial direction from the driving shaft a . The main driver u is rotated in fixed longitudinal relationship to the drums, while the pawl 9 is automatically movable or adjustable relatively to the main driver and to the drums.

In order to insure the movement of the pawl 9, relatively to the drum drivers z and 5, guiding means in this instance in the form of an annular plate or ring 11, is located between the main driver u and the tail rope drum x . An annular flange 12 is formed

in the ring 11 and surrounds the haulage drum v as indicated in Figure 1. The tail rope drum x preferably surrounds the flange 12 and in this instance a diagonal slot 13 is formed on the ring 11. The pawl 9 is preferably formed with a pin 14 which is guided in the slot 13.

In the operation of the hoist, if it be assumed that the driving shaft a is rotated in the direction of the arrow 15, in Figure 2, the main driver u will be rotated by the train of gearing described, in the opposite direction, and the pawl 9 will have been moved into engagement with one of the teeth 2 on the inner driver z thus driving the haulage drum v in the direction of the arrow 15^a. The means for moving the pawl 9 into engagement with the tooth 2 on the driver z , is the pin 14, which cooperates with the diagonal slot 13 in the guide ring 11. The tail rope drum x is disconnected from the driving shaft a , but is freely rotated in the same direction as the haulage drum v , because the rope y is unwinding from the tail rope drum.

Upon reversing the direction of rotation of the driving shaft a , the direction of rotation of the main driver u will be reversed and the pin 14 carried by the pawl 9 will move in the slot 13 in the guide ring 11 so as to engage a tooth 6 on the outer driver 5, thus driving the tail rope drum x oppositely to the direction of rotation of the driving shaft a . In such case, the haulage drum v will be freely rotated in the same direction as the tail rope drum x , as the rope y is unwound from the haulage drum.

The annular flange 12 on the guide ring 11 creates friction between the tail rope drum x and the haulage drum v , and holds the guide ring 11 stationary momentarily upon the reversal of the direction of rotation of the driving shaft a , to cause the pin 14 on the pawl 9 to move in one direction or the other in the slot 13 in the ring 11 to engage a tooth on one or the other of the drum drivers z and 5. Upon engagement of the pawl 9 with a tooth on one or the other of the drum drivers z and 5, the guide ring 11 rotates with the driven drum.

In a hoist of the character described, a brake is preferably provided for one of the drums, it being unnecessary to provide a brake for both drums in accordance with my construction. In this instance, the tail rope drum may be conveniently provided with a flange 16 to which a brake band 17 having a suitable lining 18 is applied. A brake lever 19 is fulcrumed at 20 on the lugs 21 and is connected to the ends of the brake band 17. By manipulating the lever 19 the brake will be tightened by the friction between the flange 16 on the tail rope drum x and the brake lining 18 and in this manner the rotation of the both drums may be controlled.

as long as the drums are connected through the agency of the cable and are doing work. The details of construction of this brake are not shown on the drawings, because they 5 form no part of the present invention.

I claim:

1. In a hoist, the combination of a frame, a driving shaft, two drums concentric with the driving shaft, a motor connected to operate the driving shaft, opposed drivers carried by said drums respectively, a main driver rotated by the driving shaft, a pawl carried by the main driver for automatically connecting said main driver to one or the other of the said opposed drivers in accordance with the direction of rotation of the driving shaft, and a guide member in engagement with said pawl and adapted to insure the movement of said pawl.
2. In a hoist, the combination of a frame, a driving shaft, two drums concentric with the driving shaft, one drum being rotatable upon the other drum, a motor connected to operate the driving shaft, inner and outer concentric drivers carried by said drums respectively, a main driver rotated by the driving shaft, a movable member carried by the main driver and located between the inner and outer drivers, means for automatically actuating said movable member to connect the main driver to one or the other of the inner and outer drivers in accordance with the direction of rotation of the driving shaft, and means independent of said drivers 35 for moving said movable member.

3. In a hoist, the combination of a frame, a driving shaft, two drums concentric with the driving shaft, one drum being rotatable upon the other drum, a motor connected to operate the driving shaft, inner and outer concentric drivers carried by the said drums respectively, a main driver rotated by the driving shaft, a pawl carried by the main driver and located between the inner and outer drivers, and means independent of said drivers for automatically actuating said pawl to connect the main driver to one or the other of the inner or outer drivers in accordance with the direction of rotation of the driving shaft.

4. In a hoist, the combination of a frame, a driving shaft, a motor connected to operate the driving shaft, a haulage drum and a tail rope drum concentric with the driving shaft, an inner driver in the form of a ring on the haulage drum having external teeth, an outer driver on the tail rope drum in the form of a concentric ring having internal teeth, a main driver rotated by the driving shaft, a radially movable pawl carried by said main driver and adapted to engage the teeth of the inner or outer driver in accordance with the direction of rotation of the driving shaft, and a guide ring cooperating with said pawl for insuring the movement

of said pawl in either direction the driving shaft is rotated.

5. In a hoist, the combination of a frame, a driving shaft, two drums rotatable relatively to the driving shaft, a motor connected to operate the driving shaft, opposed drivers carried by said drums respectively, a main driver connected to be rotated by the driving shaft, a pawl carried wholly by the main driver remote from the driving shaft 70 for automatically connecting said main driver to one or the other of said opposed drivers in accordance with the direction of rotation of the driving shaft, and a guide member associated with said drums and 75 adapted to cooperate with said pawl for insuring the movement of said pawl relative to each of said drivers.

6. In a hoist, the combination of a frame, a driving shaft, two drums adapted to be 85 driven alternately from the driving shaft, a motor connected to operate the driving shaft, opposed drivers carried by said drums respectively, a main driver connected to be rotated by the driving shaft, a pawl carried 90 wholly by the main driver remote from the driving shaft, a guide ring contacting with said drums, and cooperative guiding means on said pawl and ring respectively for insuring the engagement of said pawl with one 95 or the other of said opposed drivers in accordance with the direction of rotation of the driving shaft.

7. In a hoist, the combination of a frame, a driving shaft, two drums adapted to be 100 driven alternately from the driving shaft, a motor connected to operate the driving shaft, opposed drivers for the drums respectively, a main driver for the drums, a pawl 105 separate from but carried wholly by the main driver remote from the driving shaft, a guide member associated with said drums and adapted to cooperate with said pawl for insuring the engagement of said pawl with one 110 or the other of said opposed drivers in accordance with the direction of rotation of the driving shaft, and means tending to hold said guide member stationary upon the reversal of the direction of rotation of said motor.

8. In a hoist, the combination of a frame, a driving shaft, two drums adapted to be 115 driven alternately from the driving shaft, a motor connected to operate the driving shaft, opposed drivers for the drums respectively, a main driver for the drums, a pawl 120 separate from but carried wholly by the main driver remote from the driving shaft, a guide member movable with said pawl and associated with said drums and adapted to cooperate with said pawl for insuring the engagement of said pawl with one 125 or the other of said opposed drivers in accordance with the direction of rotation of the driving shaft, and means for retarding 130

the movement of said guide member when the direction of rotation of the driving shaft is reversed.

9. In a hoist, the combination of a frame, a driving shaft, two drums rotatable about said driving shaft, and adapted to be driven alternately therefrom, a motor connected to operate the driving shaft, opposed drivers for the drums respectively, a main driver for the drums, a guide ring having a diagonal slot, an annular flange on said ring located between portions of said drums, and a pawl carried by said main driver and provided with a pin extending into the slot in said guide ring, said pin and slot being adapted to cooperate to insure the engagement of said pawl with one or the other of said opposed drivers in accordance with the direction of rotation of the driving shaft.
10. In a hoist, the combination of a frame, a driving shaft, two drums rotatable about the driving shaft, a motor connected to operate the driving shaft, opposed drivers carried by said drums respectively, a main driver connected to be rotated by the driving shaft, a movable member carried by the main driver for automatically connecting said main driver to one or the other of the said opposed drivers in accordance with the direction of rotation of the driving shaft, and means independent of the opposed drivers for actuating said movable member into engagement with one or the other of the said opposed drivers.
11. In a hoist, the combination of a frame, a driving shaft, two drums rotatable about

the driving shaft, a motor connected to operate the driving shaft, opposed drivers carried by said drums respectively, a main driver connected to be rotated by the driving shaft, a movable member carried by the main driver for automatically connecting said main driver to one or the other of the said opposed drivers in accordance with the direction of rotation of the driving shaft, means independent of the opposed drivers for actuating said movable member into engagement with one or the other of the said opposed drivers, and means tending to hold said actuating means stationary upon the reversal of the direction of rotation of the motor.

12. In a hoist, the combination of a frame, a driving shaft, two drums rotatable about the driving shaft, a motor connected to operate the driving shaft, opposed drivers carried by the said drums respectively, a main driver connected to be rotated by the driving shaft, a pawl carried by the main driver for automatically connecting said main driver to one or the other of the said opposed drivers in accordance with the direction of rotation of the driving shaft, means independent of the opposed drivers for actuating said pawl into engagement with one or the other of the said opposed drivers and frictional means tending to hold said actuating means stationary upon the reversal of the direction of rotation of the motor.

In testimony whereof I have signed this 70
specification.

EARL B. LEAR.
